Primary Examiner—B. J. Bullock*Assistant Examiner*—Stacia Sinuik*Attorney, Agent, or Firm*—Harness, Dickey & Pierce, P.L.C.[57] **CLAIM**

The ornamental design for a housing design for a power nozzle, as shown and described.

DESCRIPTION

FIG. 1 is a perspective view of the housing design of the present invention;

FIG. 2 is a top view of the housing design of FIG. 1;

FIG. 3 is a front view of the housing design of FIG. 1;

FIG. 4 is a rear view of the housing design of FIG. 1;

FIG. 5 is a right side view of the housing design of FIG. 1; and,

FIG. 6 is a left side view of the housing design of FIG. 1. The broken line showing of the environmental structure is for illustrative purposes only and forms no part of the claim designed.
